MACHINE FOR MIXING CONCRETE AND
OTHER GRANULAR MATERIALS

Norman Harrison, Low Fell, England

Application February 21, 1934, Serial No. 712,421
In Great Britain January 21, 1933

6 Claims. (Cl. 83—73)

This invention relates to machines for mixing concrete and other granular materials of the kind comprising a rotary mixing pan having in the bottom of the pan a central discharge door 5 consisting of a rotary closure member mounted to rotate on one arm of a lever so that by rocking the lever in one direction the rotary member is withdrawn from the pan, while when the lever is rocked in the other direction the rotary member is brought into contact with the pan, closes the opening and rotates with the pan.

The object of the invention is to provide a simple form of door of this kind in which by one movement only the closure member is brought 15 under the opening and efficient engagement of the closure member with the opening always effected irrespective of the relative positions of the pan and the closure member, while at the same time ensuring the opening always being sealed 20 irrespective of wear and with the closure member always out of the way, so that in addition to it being possible to take full advantage of the space above the pan, the mixing means may be arranged to work over the door.

According to the invention the lever arm on which the closure member is mounted is itself pivotally mounted about a stationary fulcrum below the pan, so that to operate the door to bring it under and into the opening, and vice 25 versa, the lever is rocked only, the said closure member being in the form of a truncated cone, and the opening in the pan correspondingly tapered so that the closure member and the pan may engage after the manner of a cone clutch.

The invention will now be described by way of example with reference to the accompanying drawings, which show a portion of a concrete mixer comprising a circular discharge door. In 30 the said drawings:

- 40 Fig. 1 is a side elevation.
Fig. 2 is an end elevation.
Fig. 3 is a sectional elevation to an enlarged scale showing the door more in detail.
Fig. 4 is a plan of Fig. 3.
- 45 Fig. 5 is a diagrammatic view in elevation showing an alternative means for raising and lowering the door.
Fig. 6 is an end view of Fig. 5.

Referring more particularly to the drawings, 1 is the mixing pan and 2 a circular closure member or door of tapered section, adapted to fit into a correspondingly tapered opening in a circular flanged member 3 fitting concentrically under a central opening in the pan 1. The tapered face 50 of the door 2 is cut away at its mid-portion as

at 2a to ensure its seating hard against the member 3.

A central spindle 4 (Figs. 3 and 4) projects downwards from the door 2 and is mounted in bearings 3, 6 in a housing 7 integral with an arm 8 which is rigidly mounted on a shaft 9 extending from the bottom of the pan 1 to the side of the underframe 10 of the machine. On the outer end of the shaft 9 a relatively long weighted arm 11 is rigidly mounted at an angle such that when the door 2 is engaged with the opening in the member 3 the arm 11 is in a horizontal position so that the door is kept closed, while a lost motion connection between the arm 11 and the shaft 9 allows the former to pass the vertical position 10 when the door is opened and so maintain it open as indicated in dotted lines in Figs. 1 and 2.

With this arrangement when it is desired to close the door, there being only smooth engaging surfaces between the door 2 and the opening in the pan the door may be closed without any special care being exercised to ensure proper engagement between the closure device and the opening, while owing to the conical form of the two members 2 and 3 and effective seal is always 25 maintained irrespective of wear, although after a period of wear it may be found necessary to plane the top of the door 2 to bring it to substantially the same level as the floor of the pan 1.

The shaft 9 is shown connected by lever and link mechanism to a vertically slidable deflector blade 12 in such a manner that when the door is opened the said blade is lowered, and vice versa. This device does not form part of the present invention, and need not be described 30 further here. For a full description reference is made to my co-pending patent application No. 712,422, filed 21st February, 1934.

In order to ensure the door 2 evenly engaging the opening in the member 3, the housing 7 may 40 be mounted to float in a gimbal supported from the arm 8. This will allow the door 2 to adapt itself to any eccentricity or other irregularity between itself and the opening.

In a modification, the opening and the closure member may be of slightly oval form with the inner edge of the closure member of such dimensions that it will always enter the opening. This form gives combined positive and frictional engagement between the opening and closure 45 member.

According to another arrangement the arm of the closure member may be arranged to move in a horizontal plane or at a small angle to the horizontal, so that the door is made to move 50

sideways into and out of position underneath the opening, the arm being adapted to be swung vertically upwards to effect final closing. This form has the advantage that the door can be quickly swung clear of the opening so that no material falls on to it.

In the example shown in Figs. 5 and 6, the door 2 and its bearing 7 are mounted on a carriage 13 running on tracks 14 rigidly connected together and pivotally mounted at one end about a horizontal axis 15, while means, not shown, are provided for tilting the tracks 14 to and from the opening in the member 3. A stop 16 limits the outward travel of the carriage 13. With this arrangement, to close the door the tracks 14 are tilted by the tilting gear until the door 2 engages in the opening in the member 3. The door is opened by lowering the tilting gear and then drawing the carriage 13 along the tracks 14 out of range of the opening.

I claim:—

1. In a machine for mixing concrete and other granular materials of the kind described, comprising a rotary mixing pan having a central discharge opening of truncated conical section, a lever arm pivotally mounted on a stationary fulcrum below said pan, the axis of said fulcrum being transverse to the axis of the central discharge opening, a rotary closure member of corresponding truncated conical section adapted to fit into said discharge opening when it is desired to close said opening, and means for mounting said rotary closure on said lever arm for movement along said lever arm.
2. In a machine for mixing concrete and other granular materials of the kind described, comprising a rotary mixing pan having a central discharge opening of truncated conical section, a lever arm pivotally mounted on a stationary fulcrum below said pan, the axis of said fulcrum being transverse to the axis of the central discharge opening, a rotary closure member of corresponding truncated conical section adapted to fit into said discharge opening when it is desired to close said opening, a track on said lever arm extending transversely of said discharge opening, a carriage movable along said track, and

means for rotatably mounting said closure on said carriage.

3. In a mixing machine of the character described, a mixing pan having an opening therein, a stationary fulcrum positioned adjacent the opening in the pan and having its axis arranged perpendicular to the axis of said opening, a lever rockably mounted on said fulcrum for swinging movement toward and away from said opening, a closure for said opening, and means for mounting said closure on said lever for movement along said lever.

4. In a mixing machine of the character described, a mixing pan having an opening therein, a stationary fulcrum positioned adjacent the opening in the pan and having its axis arranged perpendicular to the axis of said opening, a lever rockably mounted on said fulcrum for swinging movement toward and away from said opening, a closure for said opening, a track on said lever, a carriage movable along said track, and means for mounting said closure on said carriage.

5. In a mixing machine of the character described, a mixing pan having an opening in the bottom thereof, a fulcrum positioned beneath said pan and laterally spaced from said opening, said fulcrum having its axis perpendicular to the axis of said opening, a lever rockably mounted on said fulcrum for swinging movement to and from a position directly underneath said opening, a closure for said opening, and means for mounting said closure on said lever for movement along said lever.

6. In a mixing machine of the character described, a mixing pan having an opening in the bottom thereof, a fulcrum positioned beneath said pan and laterally spaced from said opening, said fulcrum having its axis perpendicular to the axis of said opening, a lever rockably mounted on said fulcrum for swinging movement to and from a position directly underneath said opening, a closure for said opening, a track on said lever, a carriage movable along said track, and means for mounting said closure on said carriage.

NORMAN HARRISON.
